CLAIM

The ornamental design for a display screen with shipment management graphical user interface, as shown and described.

DESCRIPTION

FIG. 1 is a front view of a display screen with shipment management graphical user interface showing a first embodiment of my new design;

FIG. 2 is a front view of a second embodiment thereof; and, FIG. 3 is a front view of a third embodiment thereof.

The outermost broken line illustrates a display screen and the remaining broken lines illustrate portions of the shipment management graphical user interface. None of the broken lines form part of the claimed designs.
